UNITED STATES PATENT OFFICE.

EMILE BOURDELLES, OF PARIS, FRANCE, ASSIGNOR TO SCHNEIDER & CIE., OF PARIS, FRANCE.

WHEELED GUN-CARRIAGE.

1,111,785.

Specification of Letters Patent. Patented Sept. 29, 1914.

Application filed May 21, 1913. Serial No. 768,953.

To all whom it may concern:

Be it known that I, EMILE BOURDELLES, a citizen of the French Republic, and resident of Paris, France, have invented new and useful Improvements in or Relating to Wheeled Gun-Carriages, which is fully set forth in the following specification.

This invention relates to wheeled gun carriages.

10 Gun carriages have been proposed that are constituted by a frame pivoting freely by means of a male and female joint around an axis perpendicular to the longitudinal axis of the axle, in such a manner that the 15 points of support or anchoring points formed by the rear extremities of the frame are capable of yielding automatically, that is to say to move in a transverse plane independently of the points of support formed 20 by the wheels. Briefly, this arrangement has for its object to permit of the supports of the wheels and the anchoring devices of gun carriages having large firing zones to adapt themselves freely to ground of any formation 25 and to follow automatically any deformation of the ground that occurs during firing. In a particular form of a gun carriage of this kind the frame, instead of being rigid, is jointed and comprises two longitudinal branches pivoting around the axle, and a base sliding laterally by means of male and female joints upon one of the elements 30 of two universal joints the other elements of which are journaled in the longitudinal 35 branches of the frame. This arrangement while permitting of the automatic yielding of the points of support of the frame or anchoring devices relatively to the wheels and axle presents the advantage of making the 40 wheel and axle participate in resisting the recoil of the gun.

The present invention has for its object to provide particularly simple and practical constructional forms of a gun carriage of 45 the above described type.

In order that the said invention may be clearly understood, and readily carried into effect I will describe the same more fully with reference to the accompanying drawings, in which:

Figures 1 to 3 are a sectional plan on the line C—C of Fig. 2, and sections on the lines B—B and A—A of Fig. 1 respectively, showing one constructional form of the in-

vention. Fig. 4 is a plan showing another 55 constructional form of the invention, and Figs. 5 and 6 are a plan and a section on the line D—D of Fig. 5 respectively showing still another construction.

The gun carriage which is in the form of a frame comprises two longitudinal branches *a* bearing by means of a sleeve *a'* upon the axle *b*, and a base *h* adapted to pivot by means of a male and female joint (a pivot *h'* for example) in the axle *b*. The base *h* 65 receives the center pivot *g* of the top carriage carrying the gun.

In accordance with the invention, the base *h* of the frame is arranged forward of the axle, which affords wider latitude in the distribution of the loads relatively to the axle in the longitudinal direction; in other words the center of gravity of the movable portion for elevating can be located at will, with the novel arrangement, either behind 70 the axle, upon it or in front. Furthermore the novel arrangement renders it possible to cast one of the joint elements *h* in one piece at the end of the branches *a*; the base slides upon this element *h*. The construction is thus considerably simplified.

In the example illustrated in Figs. 1 to 3, each of the branches *a* of the frame carries at its front end a cylindrical trunnion *h* fitted freely in a corresponding housing of 85 a cylindrical slide block *j* movable in the direction of its length in a guide *h*² in the base *h* of the frame.

In the modification shown in Fig. 4 the pivot *g* of the top carriage supporting the 90 gun, instead of being carried by the base *h* of the frame, is carried by the axle. This modification also differs from that illustrated in Figs. 1 to 3 by the fact that the male and female joint is obtained by means 95 of a male member carried by the axle, the female element being formed in the base of the frame.

In the modification shown in Figs. 5 and 6 the base of the frame pivoting around a 100 pivot *h'* carried forward of the axle, is provided, at its ends, with teeth *h*² meshing with corresponding teeth *k* formed at the front extremities of the longitudinal branches *a* of the frame.

What I claim and desire to secure by Letters Patent of the United States is:

1. In a wheeled gun carriage, a support

ing frame comprising anchoring members revolvably mounted on the carriage axle and another member revolvably mounted on the forward side of said axle and directly engaging each of the first-named members to adapt the frame to conform with ground conformations differing from those on which the wheels may rest.

2. In a wheeled gun carriage, a supporting frame comprising anchoring members hinged to the carriage axle and another member having a pivot connection with the carriage axle on its forward side and having yielding connections with the ends of said members adapting the frame to take positions in conformity with ground conformations independent of the position of wheels and axle of the gun carriage.

3. In a wheeled gun carriage, a support-

ing frame comprising anchoring members hinged to the carriage axle and a base member having a pivot connection with the carriage axle, connections between the front ends of said members and said base, each connection comprising a pivot in one of said elements and a slideable bearing housed in the other element adapting the frame to take positions in conformity with the ground conformations independent of the position of the wheels and axle of the gun carriage.

In testimony whereof I have signed this specification in the presence of two subscribing witnesses.

EMILE BOURDELLES.
